CARL JOHAN JACKSON, OF SUPERIOR, WISCONSIN

GK

WINDOW SCREEN

Application filed August 17, 1931. Serial No. 557,642.

My present invention has reference to a fly screen for window frames, and the primary object of the invention is the provision of means whereby flies which have entered the room can be driven out through a normally closed opening in the lower portion of the screen.

A further object is the provision of a fly screen that includes a frame having an upper reticulated portion and a lower portion closed by transverse panels, one of said panels being slidable over the other panel to provide an opening therebetween and through which opening flies in a room may find an outlet.

To the attainment of the foregoing the invention consists in the improvement hereinafter described and definitely claimed.

In the drawings:

Figure 1 is a front elevation of the improvement.

Figure 2 is an enlarged sectional view approximately on the line 2—2 of Figure 1.

Figure 3 is a similar sectional view approximately on the line 3—3 of Figure 1.

The improvement contemplates the employment of a substantially rectangular frame 1 of a size to fit in the sash opening of a window casing or is of a size to be arranged alongside of the casing and mounted on runners that are fixed to the casing for vertical sliding movement. The outer face of the frame, in a line with the inner edges thereof, has tacked thereon beads 2, and the frame includes in addition to its top and bottom rails an intermediate rail 3 disposed a slight but suitable distance above its lower rail 4. A strip of molding 5 is tacked to the outer face of the outer rail 3 and there is secured to the rails and stiles of the frame at and above the rail 3, a wire mesh 6. The mesh, of course, has its edges covered by the molding strips 2 and 5.

The rails 3 and 4 have their confronting edges adjacent to their outer edges channelled longitudinally or otherwise grooved for the major portion of their length to receive therein a glass or like transparent plate 7. The grooves or channels in which the plate 7 is received are indicated for distinction by the numeral 8 and both the lower rail 4 and the

confronting faces of the rail 3 have their faces beyond the said grooves 8 provided with projections or longitudinally extending ribs 9, respectively, the said ribs having their outer ends providing the inner walls of longitudinally extending grooves 10. The ribs 9, at the portions thereof arranged over the outer end of the plate or panel 7 are cut inwardly, as at 11, toward the said panel 7 and from thence the inner walls provided by the said ribs are cut angularly, as at 12, the reduced end of the angle portions being in a line with the end of the plate or panel 7 and the second or widened end 13 terminating in a line with the inner wall provided by the grooves 10, or in other words, the thickened ends of the said angularly cut portions of the ribs are of a width equaling that of the ribs plus the thickness of the panel 7. Thus the end of the panel in reality terminates in a line with the reduced shoulders 14 provided by the angle portions of the ribs and consequently the grooves or channels 8 pass through the ribs 9 between the shoulders 11 and 14.

The ribs 9 between the shoulders 11 and the widened ends 13 thereof, together with the angle wall 12, provide the said rails 3 and 4 with oppositely disposed angle depressions 15, and in these depressions there is a transparent plate or panel 16 which normally is received between one of the stiles of the frame 1 and the shoulders 11 of the ribs 9 and is, therefore, in contact with the angle walls 12 provided by the ribs 9 and with the inner face of the transparent plate or panel 85

7. By grasping the inner end of the plate or panel 16 and swinging the same toward the outer wall 17 provided by the groove 10, the said plate or panel 16 will be brought to a line with the groove and be slid longitudinally therein, thus uncovering the opening between the end of the plate or panel 7 and one of the vertical stiles of the frame 1. When the panel 16 is thus moved any flies which may have congregated in the room may be forced out of the room through the opening left by the panel 16. The improvement not only provides for forcing flies outside of a room but both faces of the transparent plates or panels 16 and 7 may be cleaned.

The manner in which the inner faces of the panels may be cleaned is apparent. The slide-
able panel 16 is brought against the outer
wall 17 provided by the groove 10 which
leaves a space between the panel and the ribs
9 sufficient for the passage of the cleaning
rag which operates on the outer face of the
panel. By sliding the panel 16 in the guide
grooves 10 to open position a cleaning rag or
the like may be passed through the opening
and along the outer face of the panel 7 so
that both the inner and outer faces of the
panels may be cleaned without necessitating
the removal from the window casing.

15 Having described the invention, I claim:

1. A fly screen for windows comprising a substantially rectangular frame having a transverse rail secured to its stiles above the lower rail of the frame, said frame having
20 a wire mesh fixed to the transverse rail and to the portions of the frame thereabove, a transparent panel supported between the transverse rail and the lower rail of the frame and terminating a distance away from
25 one of the stiles of the frame, said transverse and lower rails having their confronting faces provided with outstanding longitudinal ribs and provided with grooves whose inner walls are afforded by the edges of said
30 walls, said ribs being cut angularly inward of the terminal end of the transparent plate, and from thence cut angularly to the inner wall provided by the groove and one stile of the frame to afford both of the rails with
35 alining angle passages, and a transparent plate received in said passages, normally contacting with the inner face of the first named transparent plate for closing the opening between the fixed plate and one of the stiles of
40 the frame and movable in its channels and through the grooves to uncover the opening between the end of the fixed plate and the said stile of the frame.

2. A window screen comprising a substan-
45 tially rectangular frame having a transverse rail secured to its stiles and above the lower rail and a mesh secured to the uppermost rail and the lower portion of the frame, a fixed transparent panel between the trans-
50 verse rail and the lower rail of the frame, said rails having their confronting faces pro-
vided with longitudinal grooves, the inner walls provided by which being beveled from
55 one of the ends thereof, and a slideable transparent panel normally received against the angle walls provided by the said portions of the grooves, whereby the slideable transparent plates will normally cover the opening be-
60 tween the fixed plates and one end of the frame and the said slideable transparent plate being movable into the restricted passages of the groove for uncovering said opening.

In testimony whereof I affix my signature.
